UNITED STATES PATENT OFFICE.

GEORGE M. CARNES, OF ROCHESTER, NEW YORK.

EDGE-SETTING MACHINE.

SPECIFICATION forming part of Letters Patent No. 792,648, dated June 20, 1905.

Application filed August 21, 1903. Serial No. 170,259.

To all whom it may concern:

Be it known that I, GEORGE M. CARNES, a citizen of the United States, residing at Rochester, in the county of Monroe, in the State of New York, have invented an Improvement 5 in Edge-Setting Machines, of which the following is a specification, reference being had to the accompanying drawings.

My invention relates to certain improvements in edge-setting machines, which improvements are fully described and illustrated in the following specification and the accompanying drawings, the novel features being specified in the claims annexed to the said 15 specification.

In the accompanying drawings, Figure 1 is a side view. Fig. 2 is a partial end view. Fig. 3 is an enlarged detail.

My improvement in machines for setting 20 or polishing the edges of shoes consists of a sliding finger-rest so placed as to enable the operator to steady the shoe while the toe is being set, the finger-rest being arranged to slide out of the way while the instep is being 25 finished, thus preventing the heel of the shoe from striking against the finger-rest and allowing the operator to set the toe and instep at one operation.

A is the frame of an edge-setting machine, 30 which may be of any desired or preferred construction, having a driving-shaft B, a suitable driving-pulley S, and an eccentric C, adapted to oscillate a pivoted member D by means of the connecting-rods Q and R, as shown in Fig. 2, attached to which is the tool-holder E, carrying the tools F and F', the tool-holder being arranged to revolve, so that either tool 35 may be brought into operation either to finish different parts of the same sole or to finish 40 unlike soles.

Attached to the frame A is a support G, into which fits a rod H, extending upward from the frame I of the finger-rest. The rod which attaches the support G to the frame A 45 is inserted in a suitable socket on said frame. The rod H is arranged so as to allow the frame I of the finger-rest to be adjusted in a vertical direction as desired, adapting the machine for use with shoes of different widths. J is 50 the finger-rest, which consists of a rod pass-

ing through the frame I and arranged to slide, as shown by dotted lines, a hook or loop being formed in one end to constitute a finger-rest for the operator. A spring K, pressing against a collar L, slides the finger-rest out of 55 the way of the heel while the instep is being finished, thus allowing the toe and instep to be set at one operation.

A set-screw M is provided, so that the finger-rest may be secured in any desired position, a keyway N and a suitable key preventing it from revolving. O is a suitable gas-burner arranged to heat the setting-tool. By the action of the spring the rest is automatically retracted as soon as released by the operator. It is retracted downwardly and backwardly from the burner, whereby heating of the rest is avoided. This function also facilitates finishing the instep in one continuous operation with the finishing of the toe. It is 70 desirable to prevent rotation of the finger-rest to keep it always in proper relation to the finger of the operator and also to hold it away from the burner and the heated tool.

In Fig. 1 the toe of a shoe is shown at P by 75 dotted lines.

I am aware that a jack or shoe-holder, in combination with a finishing-tool and its support, has been made automatically retractable, and also that reversible tool-holders adapted 80 to put either of two tools in operative position are old, and these are not my invention. My improvement provides for automatically withdrawing a finger-rest in connection with a tool-holder having tools one of which may 85 not require the use of a finger-rest.

I claim—

1. The combination in an edge-setting machine, of a finishing-tool, finger-rest, means to automatically retract said rest when relieved from the finger, a supporting device for the rest, and a burner-tube, the rest being retractable in a line oblique to and away from the tube, substantially as described, whereby when the toe is finished and the operation 95 continued toward and at the instep the rest is removed from the vicinity of the heated burner and also from the instep.

2. The combination of the main frame, frame I, the burner, fixed to and movable 100

with said latter frame, the finger-rest, both rest and burner being supported in frame I, means for adjusting the latter frame and thereby adjusting the burner and finger-rest 5 simultaneously, and the holder holding a tool adjacent the burner.

3. The combination of the main frame, frame I, the burner, the finger-rest, both rest and burner being supported in said frame I, 10 means for adjusting said latter frame and

thereby adjusting the burner and finger-rest simultaneously, means to automatically retract said rest when relieved from the finger, a supporting device for the same, and the holder holding a tool adjacent the burner.

GEORGE M. CARNES.
